SHUTTLE HOLDER

Walter A. Behrens, Jamaica, N. Y., assignor to
 Pathe Tool Manufacturing Co. Inc., Long Island
 City, N. Y., a corporation of New York

Application May 11, 1944, Serial No. 535,143

4 Claims. (Cl. 112—196)

This invention generally relates to shuttle holders for sewing or quilting machines, and is more specifically directed to improvements in shuttle holders of the so-called free floating type, such as are employed in multi-needle sewing or quilting machines operating at high speed.

In machines employing shuttle holders of this character, there is provided a drive frame or carriage suitably mounted for reciprocatory movement and comprising a pair of spaced parallel members having series of oppositely disposed aligned grooves or slots. The shuttle holders, mounted on these members, comprise a bar which carries cradles for the shuttles and is provided with studs, rivets or the like projecting therefrom for insertion into the aforementioned grooves, to locate the shuttle holder in the proper position on the carriage and to connect the same with the carriage for reciprocation therewith. The cradles may be so conformed as to fixedly support and guide the shuttles during the reciprocatory movement of the drive carriage, or they may be formed with an open side and a shuttle supporting bottom inclined toward said open side to cause the shuttles to gravitate outwardly from the cradles toward stationary races or partitions arranged intermediate adjacent cradle carrying bars, said races limiting the outward displacement of the shuttles and slidingly guiding the same during the reciprocatory movement of the carriage. Reference is herein made to the U. S. Patent No. 1,802,869 to Boettcher, wherein the aforesaid type of drive carriage and shuttle mechanism is disclosed and illustrated in detail.

While the aforesaid Boettcher construction constitutes a considerable progress in the art as compared with prior devices, because of the greatly increased speed of operation it permits to attain in machines of the aforementioned character, with the attendant obvious advantages, it is nevertheless not entirely satisfactory particularly because of the rapid wear to which certain parts of the structure are subjected during the operation of the mechanism.

It is indeed well known to those skilled in the art that, owing to the slack or play existing between the surfaces of the grooves of the carriage and the associated studs of the shuttle holders, and the high speed of operation of the machine which may reach 400 reciprocations per minute, the respective surfaces of the grooves and studs are subjected to a striking action every time the direction of the movement of the carriage is reversed, with the resulting rapid wear of the surfaces which causes defective operation

of the machine and requires frequent substitution of parts.

Up to the present time, no means had been devised for eliminating this highly objectionable wear, which constitutes a serious problem particularly in such multi-needle sewing or quilting machines in which a large number of shuttle holders are employed.

It is therefore the general object of the invention to provide novel means for preventing any objectionable wear in the associated reciprocating elements of structures of the character described, thereby insuring a prolonged life of the mechanism and a generally improved and more economical operation of the machine.

More specifically, the invention aims at eliminating any wear producing striking action of the associated surfaces of the reciprocating drive carriage and shuttle holders, and to attain this result in a simple and inexpensive manner by providing a device adapted to be incorporated in the reciprocating mechanism without substantial modification of the usual construction thereof.

It is a further important and specific object of the invention to provide spring means carried by the shuttle holders and associated with one or both of the grooved members of the drive carriage adapted to prevent any objectionable movement of the shuttle holder studs relative to the grooves into which they are inserted that would result in a striking contact between the respective surfaces, regardless of the changes in the direction of the movement of the carriage during the reciprocation of this latter.

These and other objects of the invention will become apparent in the following description of the invention illustrated in the drawing, wherein:

Fig. 1 is a perspective view of a reciprocable drive carriage for shuttle holders of a multi-needle sewing or quilting machine, to which the invention is applied, two of the shuttle holders being shown mounted on the carriage.

Fig. 2 is an enlarged fragmentary view of one of the shuttle holders of Fig. 1, illustrating one of the studs thereof and spring means associated with the stud according to the invention.

Fig. 3 is a greatly enlarged plan view, on line 3—3 of Fig. 4, of the shuttle holder and portions of the grooved members of the drive carriage on which the shuttle holder is mounted.

Fig. 4 is a greatly enlarged side elevation, partly in section, of the structure of Fig. 3.

Fig. 5 is an enlarged fragmentary side elevation, partly in section, of a shuttle holder and associated grooved member, showing additional

spring means according to a modified embodiment of the invention.

Referring now in detail to the drawing and more particularly to Figs. 1 to 4, number 10 generally indicates a shuttle driving carriage or frame for a high speed multi-needle machine, which comprises spaced parallel members 12 and a pair of spaced parallel members 14 and 15 mounted on the members 12 transversely thereof and fastened thereto to form a rigid assembly, the dimensions of the structure being, of course determined in relation to the operational requirements of the machine to which the structure is to be applied. The transverse members 14, 15 are provided along the opposed or inner sides thereof with a number of uniformly spaced slots or grooves 16, the grooves of member 14 being in alignment with the grooves of member 15, and the drive carriage, formed as described, is mounted for reciprocation in a horizontal plane, as indicated by the arrows in Fig. 1, and supported by any suitable means (not shown), the actuating mechanism for the carriage being likewise of a character known in the art and forming no part of the present invention.

The shuttle holders, two of which are shown in the drawing, are mounted on the bars 14, 15. There are as many shuttle holders as pairs of opposed grooves 16 and each shuttle holder comprises an elongated bar 18 provided with downwardly projecting studs 20, 21, suitably fastened thereto or integral therewith, the studs being spaced from one another by an amount equal to the distance between opposed series of grooves 16 and being adapted for insertion in grooves of members 14 and 15, respectively, to position the shuttle holder on the carriage and to connect the same to this latter for reciprocation therewith.

Stud 21 is formed with a central reduced portion adapted to be received in a groove of member 15 and defining a retaining head portion 24 and an enlarged portion 25 adjacent the underside of the bar 18, the purpose whereof will become hereinafter apparent.

Shuttle supporting cradles 26 are mounted on the upper face of the bar 18, said cradles being of known construction, such as disclosed in detail in the aforementioned Patent 1,802,869 to Boettcher.

A substantially U-shaped spring 28 is fastened to the underside of the bar 18, with its leg 29 clamped between the lower face of the bar and the enlarged portion 25 of the stud 21, the shorter free leg 30 of the spring extending parallel to the leg 29 in the direction of the reduced portion of the stud. The length of this free leg 30 is such that when the shuttle holder is mounted on the drive carriage by inserting the studs thereof into their respective grooves, the forward edge 31 of the leg is caused to bear against the surface of the inner side of the member 15, as shown in Figs. 3 and 4, to tense the spring, thereby urging the bar 18 of the shuttle holder toward the member 14 of the carriage and the stud 20 into firm engagement with the surface of the groove into which it is inserted.

It will be apparent that movement of the studs 20, 21 relative to their grooves, during the reciprocation of the carriage, is prevented in this manner, regardless of the play existing between the respective surfaces, and that consequently the studs cannot exert any striking against the groove surfaces, such as would otherwise occur at the

end of each stroke of the carriage due to the momentum of the shuttle holders.

In the embodiment of the invention hereinbefore described with reference to Figs. 1 to 4, a single spring is provided for each of the shuttle holder bars 18 to attain the aims to which the invention is directed; it is however understood that more than one spring may be mounted on the bars 18, to provide resilient means associated with both carriage bars 14 and 15.

Such a modified embodiment of the invention is illustrated, by way of example, in Fig. 5, wherein a further substantially U-shaped spring 32 is shown clamped between the underside of the bar 18 and a suitably enlarged portion 33 of a stud 34 inserted into a groove of the bar 14, the free leg 35 of the spring bearing against the inner side 36 of the bar 14 to function in a manner similar to that described in connection with the spring 28 associated with the bar 15. It will be apparent that other changes and modifications may be made in the structure disclosed without departing from the spirit of the invention or exceeding the scope of the claims.

I claim:

1. In a multi-needle sewing machine, having a reciprocable shuttle driving carriage comprising a pair of spaced parallel members each having a series of grooves formed along the inner side thereof, and a plurality of bars disposed upon said members transversely thereof, each of said bars carrying shuttle supporting means and being provided with a pair of spaced studs projecting therefrom for insertion into opposed grooves of said members, to position the bar on said members and connect the bar to the carriage for reciprocation therewith, the improvement which comprises at least one spring mounted on each of said bars and having a portion bearing against a surface of one of said grooved members to prevent movement of the bar relative to the grooved members during reciprocation of the carriage.

2. In a multi-needle sewing machine having a reciprocable shuttle driving carriage comprising a pair of spaced parallel members, a series of uniformly spaced grooves formed along the inner side of each of said members, and a plurality of bars disposed upon said members transversely thereof, each of said bars carrying shuttle supporting means and being provided with a pair of spaced studs projecting therefrom for insertion into opposed grooves of said members, to position the bar on said members and connect the bar to the carriage for reciprocation therewith, the improvement which comprises at least one spring mounted underneath each bar and adapted to engage the inner side of one of said grooved members to prevent movement of the bar relative to the grooved members during the reciprocation of the carriage.

3. In a multi-needle sewing machine having a reciprocable shuttle driving carriage comprising a pair of spaced parallel members, a series of uniformly spaced grooves formed along the inner side of each of said members, and a plurality of bars disposed upon said members transversely thereof, each of said bars carrying shuttle supporting means and being provided with a pair of spaced studs projecting therefrom for insertion into opposed grooves of said members, to position the bar on said members and connect the bar to the carriage for reciprocation therewith, the improvement which comprises spring means associated with each bar and said grooved

members for preventing movement of the studs relative to the grooves into which they are inserted during reciprocation of the carriage, said means comprising at least one substantially U-shaped spring fastened to the bar and having a leg in engagement with a surface of one of said grooved members.

4. In a multi-needle sewing machine having a reciprocable shuttle driving carriage comprising a pair of spaced parallel members, a series of 10 uniformly spaced grooves formed along the inner side of each of said members, and a plurality of bars disposed upon said members transversely thereof, each of said bars carrying shuttle sup-

porting means and being provided with a pair of spaced studs projecting therefrom for insertion into opposed grooves of said members, to position the bar on said members and connect the bar to the carriage for reciprocation therewith, the improvement which comprises a substantially U-shaped spring mounted underneath each bar, one leg of said spring bearing against the inner side of one of said grooved members to tense the spring so as to urge the bar toward the other member, whereby to prevent movement of the bar studs relative to their grooves during reciprocation of the carriage.

WALTER A. BEHRENS.
